LATHER PRODUCING MACHINE

Albert B. Campbell, Chicago, Ill., assignor to
Alphons J. Sumkowski, Chicago, Ill.

Application March 14, 1938, Serial No. 195,886

2 Claims. (Cl. 259—10)

My invention relates to a machine for producing a lather from liquid soap.

My objects, generally stated, are to provide a novel, simple, and inexpensive construction of machine for quickly producing lather, as for example, and more particularly, for use in shaving, which will be of the desired consistency.

Referring to the accompanying drawings:

Figure 1 is a view in longitudinal sectional elevation of a machine embodying my invention, certain parts of the same being shown in elevation and the section being taken at the line 1 on Fig. 5 and viewed in the direction of the arrow.

Figure 2 is an enlarged fragmentary sectional view taken at the line 2 on Fig. 1 and viewed in the direction of the arrow.

Figure 3 is a similar view taken at the line 3 on Fig. 2 and viewed in the direction of the arrow.

Figure 4 is a sectional view taken at the line 4 on Fig. 1 and viewed in the direction of the arrow; and

Figure 5, an end view of the machine, the machine being viewed from the left-hand side of Fig. 1.

Referring to the preferred illustrated embodiment of my invention, the machine comprises a receptacle 6 for liquid soap and having a removable and replaceable cover 7; a valve casing 8 located at one end of the receptacle 6 and opening into the latter through a vertical slot 9 in the adjacent end wall of the receptacle; a valve 10 reciprocably mounted in the valve casing 8; a chamber 11 extending along the bottom of the receptacle 6 and having an inlet 12 at one end opening at a tapered seal-forming portion 13 into the bottom of the valve casing 8, and an outlet 14 at its opposite end; means 15 for lathering the soap fed into the chamber 11 and feeding it in the form of lather through the outlet 14; a power device 16, shown as an electric motor, for operating the lathering and feeding means 15; and means 17 for heating the soap in the chamber 11 and receptacle 6.

The valve casing 8, shown as formed integrally with the walls of the receptacle 6, chamber 11 and the base 18 of the machine, contains a bushing 19 screwed into the upper end of the casing 8 and through which the stem 20 of the valve 10 slides. The valve 10 is provided at its upper end with an annular flange 21 which forms an abutment for one end of a coil spring 22 surrounding the valve 10, the other end of this

spring engaging an inwardly extending annular shoulder 23 in the lower portion of the casing 8, the spring 22 tending to hold the valve 10 in open position and away from the seat 13 with which it cooperates.

The chamber 11 is of cylindrical form and its outlet 14 which is located at the top of the chamber is elongated crosswise of the chamber to cause the lather discharged through it to issue in ribbon form, though this is not essential to the invention.

The means for lathering and feeding the soap to the outlet 14 are shown as comprising a screw 24 preferably of such diameter as to provide an annular clearance entirely around it between the screw and the cylindrical wall of the chamber 11, which forms a sleeve for the screw as represented at 25. The screw 24, shown as reaching short of the outlet end of the chamber 11, is provided at its opposite end with a cylindrical portion 26 journaled in the adjacent open end of the chamber 11 at which portion the screw connects with the shaft 27 of the electric motor 16, the casing of which is connected with lugs 28 having flanges 28a on the body of the machine.

The screw 24 is preferably of the plural parallel thread type, two such threads, 29 and 30, starting at diametrically opposed points at the end of the screw, being employed in the construction shown, the threads 29 and 30 being preferably of relatively great depth as shown.

It has been found in practice that a very satisfactory screw to use is one of approximately $\frac{3}{4}$ in. in diameter and approximately $\frac{3}{8}$ in. pitch, with the central core portion 31 approximately $\frac{3}{8}$ in. in diameter, thus causing the threads 29 and 30 to be of relatively great depth, with a crosswise taper of the threads of approximately 1°.

The construction of heating means shown comprises a member 32 of current insulating material, such as porcelain, of segmental cylindrical form to adapt it to be slid into a space 33 of similar cross section provided in the body of the machine and partially surrounding the chamber. The member 32 has an arcuate series of openings 34 extending lengthwise of the member and parallel with each other, in which openings coils 35 of electric resistance wire are confined, these coils being suitably connected together, as for example in series for connection with any suitable source of current supply for generating the desired degree of heat.

The opening and closing of the valve 10 is

preferably controlled through the medium of the same mechanism that controls the supplying of current to the motor 16. In the arrangement shown this is effected by positioning the swinging lever 36 of the switch 37 controlling the flow of current to the motor 16, above the valve stem 20 and so positioning these parts that when the lever 36 is swung down to cut off the supply current to the motor 16 (in which position the lever 10 36 remains), the valve 10 will be forced against the seat 13 to close the inlet 12 to the receptacle 6, in which position the spring 22 will be compressed; and when the switch lever 36 is swung upwardly to the position shown in Fig. 1, to supply current to the motor 16, the valve 10 will be in open position, it having been moved to this position by the expansion of the spring 22.

The operation of the machine is as follows:

Liquid soap having been supplied to the receptacle 6, the operator to effect discharge of lather through the outlet 14, throws the switch lever 36 to the position shown in Fig. 1 thus opening the receptacle 6 to the chamber 11 and supplying current to the motor 16, which, by 25 way of example, has an idling speed of about 16,000 R. P. M., when disconnected from the screw, which rapidly rotates the screw device 24. The liquid soap flows from the receptacle 6 into the chamber 11 in which it is engaged by the 30 screw device 24 which operates to whip the soap and feed it toward the outlet. The action of the screw 24 produces a suction in the chamber 11 which draws air therein by leakage around the cylindrical portion 26. It is obvious that each 35 increment of air and lathering medium is segregated from further supplies of air as well as from additional lathering medium while it is driven forward within the screw at high speed. As a result, a lather consisting of extremely fine 40 bubbles is produced which will last for extraordinarily long periods. The screw in acting on the soap causes it to become in the condition of a lather, in which form it issues from the outlet 14 for use, it having been found in practice a sufficient amount of lather for properly covering 45

the face of a person to be shaved and of the desired consistency, may be very quickly produced.

The valve 10 is preferably made adjustable for controlling the flow of soap to the chamber 11. This is effected in the construction shown by means of the bushing 19 which is adjustable at its threaded connection with the casing 8 into different vertical positions. By adjusting the bushing 19 from the full valve-open position shown in Fig. 1, to a position in which the bushing extends at its lower surface below the position occupied by the upper surface of the flange 21 when the valve, under the control of the switch lever 36, is in its full-open position, the bushing forms a stop for the flange 21 limiting 15 upward movement of the valve; it thus being possible to attain, by adjustment, any desired degree of opening of the valve.

While I have illustrated and described a particular machine embodying my invention, I do not wish to be understood as intending to limit it thereto as the same may be variously modified and altered and the invention embodied in other forms of structure without departing from the spirit thereof.

What I claim as new, and desire to secure by Letters Patent, is:

1. In a lathering machine, a receptacle for a liquid lathering medium, a sleeve, a screw within the sleeve, means for rapidly rotating the screw, said receptacle having a restricted liquid outlet communicating with one end of the screw, said end of the screw being accessible to air, and a lather outlet at the other end of the screw.

2. A lathering device comprising a receptacle for liquid lathering medium having an outlet in a lower portion thereof, a cylindrical chamber below the receptacle, restricted means for feeding lathering medium to the chamber, a screw substantially filling said cylindrical chamber, a lathering outlet from said chamber, and means for rotating said screw, the screw being arranged in the chamber to permit restricted access of air thereto.

ALBERT B. CAMPBELL.
